UNITED STATES PATENT OFFICE.

GEORGE LIDDELL, OF LONDON, ENGLAND.

TOILET FIXTURE.

Application filed December 20, 1921. Serial No. 523,680.

To all whom it may concern:

Be it known that I, GEORGE LIDDELL, of 67 Stockwell Park Road, Clapham, London, S. W. 9, England, a British subject, have 5 invented a certain new and useful Improved Toilet Fixture, of which the following is a specification.

This invention relates to toilet fixtures of the kind wherein a roll of toilet paper is 10 mounted upon a roller the ends of which are rotatably and detachably carried by a pair of brackets projecting from a backplate, and has for its object to provide an improved fixture of simple construction which whilst 15 being easy of access for re-filling, is adapted to prevent theft both of the toilet roll and the fitting itself.

According to this invention each bracket is formed with a longitudinal slot adapted 20 rotatably to support one end of the roller said slot having an upwardly opening branch at each end, the mouth of that branch at the outer end being closed by a spring influenced detent adapted to permit 25 the insertion into but not the extraction from said slot, of the end of the roller.

Preferably the mouth of the slot at the outer end of each bracket is at such a distance from the back plate as just to permit 30 the insertion of the roller with a full sized roll of paper and the inner mouth of said slot is at such a distance from said back plate as to prevent the extraction of the roller until the roll of paper is exhausted. 35 Preferably also the means for securing the fixture to its support is so arranged as to be accessible only when the roller has been removed.

One form of the invention will be described with reference to the accompanying drawings of which Figure 1 is a front elevation, Figure 2 is a plan and Figure 3 is 40 an end elevation with a portion of the bracket broken away more clearly to show 45 the construction.

A back plate *a* of wood or other suitable material has a pair of obtuse angled sheets metal brackets *b*, *b* of substantially triangular shape secured to it by means of screws *d* 50 or the like passing through inwardly directed flanges *c*, *c*, formed on said brackets *b*, *b* one of the screws *d* or the like of each bracket *b* passing through the backplate *a* into the door, wall or other support (not 55 shown) and serving to retain the fitting in position. The upper marginal portion of

each bracket *b* is bent outwards at right angles along each of two parallel lines so as to form a channel section flange *e*, whilst an extension of said marginal portion is bent 60 so as to form a tongue *f* adapted to be secured to the back plate *a* by means of a screw *g* or the like. A longitudinal slot *h* is formed in each bracket *b* parallel with its upper edge, said slot *h* having a transverse 65 branch *j* near the inner end of the bracket *b* communicating with a transverse slot *k* in the upper surface of the flange *e* and having a re-curved portion *m* at its outer end communicating with a transverse slot *n* in 70 the upper surface of the flange *e* near its outer end.

An upwardly projecting tongue *p* is provided at the rear edge of each slot *n* by pressing up the metal during the formation 75 of said slot and a leaf spring *q* secured in juxtaposition to the under side of each flange *e* by means of rivets *r*, *r* or the like, extends across the under side of the slot *n*.

A roller *s* of wood or other suitable mate- 80 rial is provided with a pair of coaxial pivot pins *t*, *t* adapted to pass through the slots *h*, *h* and their connections and is adapted to form a spindle for a roll of toilet paper *u*. The brackets *b* are so spaced on the back 85 plate *a* as to permit the free insertion of the roll *u* therebetween and the radial distances of the centre lines of the slots *k* and *n* from the base plate *a* are respectively equal to the radii of the roller *s* and the roll *u*. The roller 90 *s* is inserted within a roll of toilet paper *u* and is placed between the brackets *b*, *b* so that the pins *t*, *t* rest on the outer ends of the adjacent flanges *e*, *e* and against the tongues *p*, *p*. The roll *u* is then pressed downward. 95

ly so that the pins *t*, *t* bend the springs *q*, *q* and are admitted to the slots *h*, *h* through the recurved portions *m*, *m*, the springs *q*, *q* returning to their normal positions after 100 the passage of the pins *t*, *t*. The toilet paper may then be used as required, the pins *t*, *t* revolving in the slots *h*, *h* and gradually sliding towards the back plate *a* as the paper is expended. When the roll *u* has been exhausted the pins *t*, *t* will 105 have reached a position below the slot *k* and the roller *s* may be removed for the purpose of re-filling the appliance. Since the springs *q*, *q* extend across the slots *n*, *n* it is extremely difficult to remove the roller *s* and 110 roll of paper *u* by withdrawing the pins *t*, *t* through said slots *n*, *n* and as the roller *s*

can only pass through the slots *k*, *k* when the paper is exhausted it is practically impossible for the roll of paper *u* to be abstracted from the appliance excepting by 5 the usual unwinding process.

Preferably those screws *d* or the like which are normally obscured by the roller *s* or roll *u*—i. e. the upper ones—are used for securing the appliance and its base plate *a* 10 to the support, in order to prevent the removal of the appliance when carrying a roll of paper *u*.

If desired the back plate *a* may be formed integrally with the brackets *b*, *b*, e. g. by 15 casting or stamping or a wooden backplate *a* may be provided with a covering of metal or other suitable material, said covering being formed with holes for the positioning and reception of the screws *d* and *g*. Also 20 the brackets *b*, *b* may be formed from a single sheet of metal or the like, the flanges *c*, *c* being integral with one another and forming a distance piece for spacing the brackets *b*, *b*.

25 By forming the brackets *b*, *b* so that the longitudinal slots *h*, *h* incline downwardly towards their inner ends, the outer surface of the roll of toilet paper *u* is constrained to bear against the back plate *a* and is prevented from rotating unduly thus preventing waste due to the delivery of an excess of 30 paper.

I claim:—

1. A toilet fixture of the kind set forth 35 wherein each bracket is formed with a longitudinal slot adapted rotatably to support one end of the roller said slot having an upwardly opening branch at each end, the mouth of that branch at the outer end being 40 closed by a spring-influenced detent adapted

to permit the insertion into but not the extraction from said slot of the end of the roller.

2. A toilet fixture as claimed in claim 1, wherein that mouth of the slot at the outer 45 end of each bracket is at such a distance from the back plate as just to permit the insertion of the roller with a full sized roll of paper and the inner mouth of said slot is at such a distance from said back plate as to 50 prevent the extraction of the roller until the roll of paper is exhausted.

3. A toilet fixture as claimed in claim 1, wherein the means for securing the fixture to its support is so arranged as to be accessible only when the roller has been removed, 55 substantially as and for the purpose set forth.

4. A toilet fixture as claimed in claim 1, wherein an upwardly projecting tongue *p* is 60 provided at the rear edge of each slot *n* so as to form a guide-stop for the ends of the roller.

5. A toilet fixture as claimed in claim 2, wherein the means for securing the fixture 65 to its support is so arranged as to be accessible only when the roller has been removed, substantially as and for the purpose set forth.

6. A toilet fixture as claimed in claim 2, 70 wherein an upwardly projecting tongue *p* is provided at the rear edge of each slot *n* so as to form a guide-stop for the ends of the roller.

7. A toilet fixture as claimed in claim 3, 75 wherein an upwardly projecting tongue *p* is provided at the rear edge of each slot *n* so as to form a guide-stop for the ends of the roller.

GEORGE LIDDELL.
